[57] CLAIM

The ornamental design for a push-to-talk wireless telephone, as shown and described.

DESCRIPTION

FIG. 1 is a front, bottom, and right side perspective view of a push-to-talk wireless telephone showing our new design.

FIG. 2 is a front side elevational view thereof.

FIG. 3 is a left side elevational view thereof.

FIG. 4 is a top side plan view thereof.

FIG. 5 is a right side elevational view thereof.

FIG. 6 is a back elevational view thereof; and,

FIG. 7 is a bottom plan view thereof.

The broken lines throughout the views are for illustrative purposes only and form no part of the claimed design. The broken lines which encompass unshaded portions of the article define the boundaries of, but are not included in, the claimed design.
